SELF SUSTAINING FABRICATED REENFORCING SYSTEM

Peter H. Sereff, Lima, Ohio

Application November 6, 1929. Serial No. 405,096

23 Claims. (Cl. 72—66)

My invention relates to building constructions.

It is the object of my invention to provide a self-supporting, load-carrying, concrete reenforcement that serves the multiple purpose of a joist carrying a load, a concrete supporting member, a floor support and a ceiling support.

It is my object to provide a building construction of poured concrete without shores, in which the load is carried from wall to wall by the same fabricated truss that positions the ceiling and floor members and any concrete associated therewith thereby saving the time of erecting shores and forms and waiting for their removal.

It is a further object of my invention to provide either permanent or detachable soffit members which hold in position metal fliers and arches or tile ceiling liners or tile filler blocks.

It is a further object to provide removable soffits which can be quickly detached and, when removed, leave a ceiling finish that is smooth and ready for the ceiling decorations.

It is my further object to provide a construction which is adaptable to either corrugated ceilings or smooth ceilings.

It is a further object to provide structural joist members with detachable soffits and permanent soffits so that variations in length of ceilings or distance between walls may be accommodated with a standard construction.

30 Referring to the drawings:

Figure 1 is a side elevation of the fabricated self-sustained reenforcing unit;

Figure 2 is an end view thereof;

Figure 3 is a section of a removable, steel core formed construction;

Figure 4 is a section of similar construction employing a terra cotta ceiling and the permanent steel core form;

Figure 5 is a section showing the use of terra cotta tile block filler;

Figure 6 is a section through a solid concrete flat slab construction;

Figure 7 is a longitudinal section of the reenforcement and cross section of steel I-beams showing the method of supporting the joist on the steel I-beam;

Figure 8 is a similar view where a reenforced concrete beam is employed;

Figure 9 is a similar view showing a support on a masonry wall;

Figure 10 is a perspective view of the metal portions of my invention arranged for pouring;

Figure 11 is a perspective of the temperature expansion rod;

55 Figure 12 is an isometric perspective showing

the assembly of I-beams, concrete metal cores and terra cotta ceiling;

Figure 13 is a section on the line 13—13 of Figure 1.

Referring to the drawings in detail, the self-sustained, fabricated, reenforcing beam is formed of deformed bars. The bottom bar is designated 1 which extends from end to end of the structure. The top bar is designated 2. Bars 1 and 2 are secured together by welding to them the diagonal rod 7. Thus, one-half of the reenforcing unit is manufactured. Likewise the bottom bar 3 being bent a predetermined distance from each end with inclined portions 5 and horizontally extending portions 6, which latter portions are welded to the top bars. Vertical web rods 8 are placed in position and welded at the bottom to the bottom bar 3 and at the top to the top bar 4, thus completing the other half of the unit.

It will be noted that the point of departure from the bottom and the point of arrival of the bar 3 at the top, where the diagonal portion 5 is used for this purpose, are points where the vertical web rods 8 are located.

A similar vertical web rod 8 is located at the center of the span. Thus, two fabricated members composing the truss are welded together at intervals.

Suitable spacers are provided between the bottom bars 1 and 3 and the top bars 2 and 4 to give space between them for adequate joining of the concrete and to provide a space for receiving the temperature expansion rods 9a. The shear plates 9 are secured in the space between the top bars 2 and 4. This shear plate 9 is provided with the angle members 10. The bottom flanges of the angle members 10 form a horizontal base to which is secured the permanent soffit 11. The bottom bar 1 is welded adjacent its end to the vertical web of the angle 10.

The permanent soffit 11 is welded as indicated having upturned ears 12. The detachable soffit 14 is adapted to cooperate with the permanent soffit so that there will be a continuous space provided, as hereinafter described.

Arch-shaped steel forms 14a are mounted within the upturned flanges 15 of the soffits 14 for supporting them in position. The soffits themselves are suspended by the interlocking brackets 16, the upper ends of which are formed in hooks 17 beneath which are laterally extending fingers 18. The lower ends of these brackets 16 are also formed with hooks 19 which extend outwardly through slots in the soffits. De-

tachable wires 20 are inserted in the hooks 19 beneath the soffits to hold the soffits in position. These hook members 19 may be single or double, as indicated.

5 These soffits are provided with overturned edges 21 which serve to support the angle strips 22 on the shoulders 23, on which are supported the tile filler blocks 24 when the steel forms 14a are not used. The inner ends of these strips, as 10 at 25, are embedded in the concrete.

The turned over ends 21 of the soffits may also be used for supporting the filler plates 26 whose downwardly extending margins 27 rest within the turned over edges 21 of the soffits. It will 15 be noted that the soffits may be either inverted or right side up depending upon the use to be made of them.

In the form shown in Figure 4 the ceiling plates of tile designated 28 are provided with 20 slots 29 for receiving the lower edges of the steel forms 14a, a portion of the tile extending at 30 between the grooves 29 directly over the soffits thus forming the wedge shaped projection into the concrete designated 31. This column of concrete 25 constitutes a part of the joist that rests upon the walls 32.

The fabricated, self-sustained reinforcing unit 30 may rest directly on the concrete wall 32 with it reenforcing 33 as indicated in Figure 3 or it may rest upon the I-beam 34 in the wall 32 by reason of the bracket 35 which is welded between the rods 2 and 4 at the extreme ends of the self-sustained, fabricated member. 37 designates the spacer member between the upper bars 35 and 38 the spacer member between the lower bars.

Operation

The two units consisting of the top and bottom bars 1 and 2 and the top and bottom bars 3 and 4 are assembled in welded condition. The 40 end plates 9 and permanent soffits 11 are installed. Such members are spaced apart with their ends resting upon the walls 32. The forms 14a and the soffits 14 are placed in position together with the tile members either 28 or 24 or the filler member 26. The concrete is then 45 poured without the use of shores. After the concrete is poured the soffits may be removed by pulling the pins 20 and the steel forms 14a 50 may be removed if the arrangement shown in Figure 3 is used.

If the arrangement shown in Figure 4 is used, then the soffits may be removed but the forms 55 14a will remain in place.

In the form shown in Figure 5 the soffits will remain if desired, otherwise they may be removed.

The same is true of Figure 6.

60 Thus, with the same standard construction spaced with the temperature spacing bars 9a the entire floor can be poured resting upon the walls without the use of shores producing a smooth ceiling or a corrugated ceiling or a sound 65 proof ceiling as desired depending upon the precise arrangement of the interchangeable parts. The truss structure enables the load to be carried while, at the same time, provides the reenforcement for the concrete. All the advantages 70 of a concrete construction are secured. The parts are fabricated in a factory accurately, are delivered to the job in numbered condition and are arranged in accordance with the architect's specification. They are exactly in position vertically, being positioned by the temperature 75

spacing rods 9a. Thus, the reenforcing system is delivered to the job completely fabricated. All of the difficulty with labor and material necessary to erect temporary wood forms and shoring now utilized in poured concrete constructions is eliminated. All the delay and expense necessary to select from the carload of wires and other reenforcing material heretofore employed is eliminated.

The danger of insufficient reenforcement which always confronts the architect with the present type of reenforcing material is absent because the positioning of the present load-supporting parts is positive and mathematically exact; it does not depend upon the judgment of common labor or of foreman as to the placing of the units.

The temperature expansion rods are arranged from twelve to eighteen inches apart. The result is a concrete joist 31 and a floor slab 36 90 integral with one another.

The core forms and soffits can be used over and over again. If it is desired to plaster the ceiling, the rods 20 which are mounted in the hooks 19, after the soffits have been removed, 100 are utilized as a means of sustaining the wire lath upon which the plaster is placed.

Thus, air is allowed to circulate behind the metal lath throughout its length and prevents discoloring of the plaster because there is air 105 in one place and solid material in another.

The forms 14a are preferably made from six to fourteen inches in depth and one, two or three feet in length; the dimensions may be varied to suit the demands of the construction.

When the soffits are removed the hooks 19 are taken off if they are not to be used for suspending the metal lath. Then the ceiling is plastered in the usual manner.

It will be understood that I desire to comprehend within my invention such modifications as may be necessary to adapt it to varying conditions and uses.

Having thus fully described my invention, what I claim as new and desire to secure by Letters Patent, is:—

1. In a self-sustaining, reenforcing unit, a top and a bottom bar, truss members therebetween, a laterally-disposed bottom bar having upwardly-extending ends projecting to a point 125 adjacent to and parallel with the first mentioned top bar and web rods supporting the last-named bottom bar from the top bar.

2. In a self-sustaining, reenforcing unit, a top and a bottom bar, truss members therebetween, a laterally-disposed bottom bar having upwardly-extending ends projecting to a point 130 adjacent to and parallel with the first mentioned top bar, a second top bar parallel with the first bar and welded thereto at intervals, 135 and web rods supporting the last-named bottom bar from the top bars.

3. In a self-sustaining, reenforcing unit, a top and a bottom bar, truss members therebetween, a laterally-disposed bottom bar having upwardly-extending ends projecting to a point 140 adjacent to and parallel with the first mentioned top bar, a second top bar parallel with the first bar and welded thereto at intervals, and vertically-disposed members at intervals 145 welded to and between said second top bar and the laterally disposed bottom bar to maintain them in spaced relationship.

4. In a self-sustaining, reenforcing unit, a top and a bottom bar, truss members there-

- between, a laterally-disposed bottom bar having upwardly-extending ends projecting to a point adjacent to and parallel with the first mentioned top bar, a second top bar parallel with the first bar and welded thereto at intervals, and vertically-disposed members at intervals welded to and between said second top bar and the laterally disposed bottom bar to maintain them in spaced relationship, diagonally-disposed end plates at the ends of said fabricated members extending downwardly and outwardly from a point remote from the top to a point adjacent the termination of the lower ends. 5. In a self-sustaining, reenforcing unit, a top and a bottom bar, truss members therebetween, a laterally-disposed bottom bar having upwardly-extending ends projecting to a point adjacent to and parallel with the first mentioned top bar, a second top bar parallel with the first bar and welded thereto at intervals, and vertically-disposed members at intervals welded to and between said top bar and the second-named bottom bar to maintain them in spaced relationship, diagonally-disposed end plates at the ends of said fabricated members extending downwardly and outwardly from a point remote from the top to a point adjacent the termination of the lower ends, bearing flanges welded to the lower ends of said diagonal plates. 30. 6. In a self-sustaining, reenforcing unit, top and bottom bar, truss members therebetween, a laterally-disposed bottom bar having upwardly-extending ends projecting to a point adjacent to and parallel with the first mentioned upper bar, a second top bar parallel with the first bar and welded thereto at intervals, and vertically-disposed members at intervals welded to and between said top and bottom bars to maintain them in spaced relationship, diagonally-disposed end plates at the ends of said fabricated members extending downwardly and outwardly from a point remote from the top to a point adjacent the termination of the lower ends, bearing flanges welded to the lower ends of said diagonal plates and permanent soffits on the bottom of said bearing members. 45. 7. In a self-sustaining, reenforcing unit, a top and bottom bar, truss members therebetween, a laterally-disposed bottom bar having upwardly-extending ends projecting to a point adjacent to and parallel with the first mentioned top bar, a second top bar parallel with the first bar and welded thereto at intervals, and vertically-disposed members at intervals welded to and between said top and bottom bars to maintain them in spaced relationship, diagonally-disposed end plates at the ends of said fabricated members extending downwardly and outwardly from a point remote from the top adjacent the termination of the lower ends, bearing flanges welded to the lower ends of said diagonal plates, diagonally-disposed bearing members located between the top bars and between the ends of said bars and said diagonal plate whereby a bearing support is provided between the upper and lower ends of bars at the ends of the fabricated member. 60. 8. In combination, an upper and lower bar, diagonally-disposed truss members welded therewith connecting said bars, a second upper bar located in spaced relationship to the first upper bar, a second lower bar, depending vertical bars located between the upper second bar extending to the second lower bar, the outer ends of said second lower bar being directed upwardly diagonally to a point adjacent the ends of the upper bars and extending parallel thereto to the ends of the upper bars. 80. 9. In combination, an upper and lower bar, diagonally-disposed truss members welded therewith connecting said bars, a second upper bar located in spaced relationship to the first upper bar, a second lower bar, depending vertical bars located between the upper second bar extending to the second lower bar, the outer ends of said second lower bar being directed upwardly diagonally to a point adjacent the ends of the upper bars and extending parallel thereto to the ends of the upper bars, downwardly and outwardly disposed diagonal plates located between the upper bars and extending to the level of the lower bars. 85. 10. In combination, an upper and lower bar, diagonally-disposed truss members welded therewith connecting said bars, a second upper bar located in spaced relationship to the first upper bar, a second lower bar, depending vertical bars located between the upper second bar extending to the second lower bar, the outer ends of said second lower bar being directed upwardly diagonally to a point adjacent the ends of the upper bars and extending parallel thereto to the ends of the upper bars, downwardly and outwardly disposed diagonal plates located between the upper bars and extending to the level of the lower bars. 90. 11. In combination, an upper and lower bar, diagonally-disposed truss members welded therewith connecting said bars, a second upper bar located in spaced relationship to the first upper bar, a second lower bar, depending vertical bars located between the upper second bar extending to the second lower bar, the outer ends of said second lower bar being directed upwardly diagonally to a point adjacent the ends of the upper bars and extending parallel thereto to the ends of the upper bars, downwardly and outwardly disposed diagonal plates located between the upper bars and extending to the level of the lower bars, and laterally extending flanges formed on said plates. 105. 12. In combination, an upper and lower bar, diagonally-disposed truss members welded therewith connecting said bars, a second upper bar located in spaced relationship to the first upper bar, a second lower bar, depending vertical bars located between the upper second bar extending to the second lower bar, the outer ends of said second lower bar being directed upwardly diagonally to a point adjacent the ends of the upper bars and extending parallel thereto to the ends of the upper bars, downwardly and outwardly disposed diagonal plates located between the upper bars and extending to the level of the lower bars, and laterally extending flanges formed, on said plates, a vertically-extending bar extending from the upper ends of said plates to the lower level thereof and permanent soffits connected to said flanges and to the lower end of the vertical bars. 110. 13. In combination, a fabricated, self-sustained, reenforcing unit comprising upper bars and lower bars and temperature spacing bars connecting said units in parallel relationship, the ends of said temperature bars being inserted between the upper bars of the reenforcing unit as described, bracket members mounted on the lower bars of said unit, detachable soffits supported by said bracket members and forming members carried by the soffits. 115. 14. In combination, self-sustained, reenforcing units, one of which has upper and lower bars and is diagonally braced between upper and lower bars and the other of which has upper and lower bars and vertical bars located between the upper and lower bars, and bearing plates connected to both upper bars where they are assembled at the top of the reinforcing units, said bearing members resting on the I-beams. 125. 15. In combination, self-supporting, fabricated truss, reenforcing members, the ends of which rest on walls, detachable soffits suspended there- 130. 16. 135. 17. 140. 18. 145. 19. 150.

- from, arcuate forms carried on said soffits, and means to space said reenforcing members to maintain them in parallel relationship, diagonally disposed load carrying plates at the ends of each truss, and permanent end soffits attached to the load carrying plates.
15. In combination, a reenforcing unit comprising upper and lower bars and diagonal braces, a second reenforcing unit welded thereto in spaced relationship comprising upper and lower bars and vertical braces, means to maintain the upper and lower bars in spaced relationship, the lower bars being further apart than upper bars.
15. 16. In combination, a reenforcing unit comprising upper and lower bars, diagonal braces, a second reenforcing unit welded thereto in spaced relationship comprising upper and lower bars and vertical braces, means to maintain the upper and lower bars in spaced relationship, the lower bars being further apart than the upper bars, the ends of the last mentioned lower bar being diagonally disposed upwardly and thence horizontally parallel to the upper bars.
15. 17. In combination, a reenforcing unit comprising upper and lower bars, diagonal braces, a second reenforcing unit welded thereto in spaced relationship comprising upper and lower bars and vertical braces, means to maintain the upper and lower bars in spaced relationship, the lower bars being further apart than the upper bars, the last mentioned lower bar at the ends being diagonally disposed upwardly and thence horizontally parallel to the upper bars, and a vertical brace at either end depending from the point where the lower bar joins the upper bars.
18. In combination, a reenforcing unit comprising upper and lower bars, diagonal braces, a second reenforcing unit welded thereto in spaced relationship comprising upper and lower bars and vertical braces, means to maintain the upper and lower bars in spaced relationship, the lower bars being further apart from the upper bars, the last mentioned lower bar at the ends being diagonally disposed upwardly and thence horizontally parallel to the upper bars, a vertical brace at either end depending from the point where the lower bar joins the upper bars, diagonally disposed plates ex-
- tending downwardly and towards the end of the unit from a point where the brace joins the upper bars, bearing plates attached thereto, and permanent soffits connected to the lower ends of said vertical bars and said plates.
19. In combination, vertical walls, self-sustained, reenforcing truss units having the ends resting on side walls, spacing rods maintained in said units in spaced relationship, soffits suspended from said units and hollow tile blocks carried by the edges of said soffits between said units, said blocks having corrugated sides for engaging with the concrete poured around the sides and top of said units and tiles.
20. In combination, a plurality of parallel, spaced, self sustained, reenforcing units of the character described, spacing members for maintaining them in parallel relationship, soffits carried by said units, filler plates carried by said soffits.
21. In combination, a plurality of parallel, spaced, self sustained, reenforcing units of the character described, spacing members for maintaining them in parallel relationship, soffits carried by said units, filler plates carried by said soffits, said soffits and plates being rendered detachable from the units so that they may be removed after pouring.
22. In combination, reenforcing, self-sustained girders, one of which comprises upper and lower horizontal members having diagonal interconnecting braces and the other of which comprises horizontal, spaced members interconnected by vertical braces, said two units being arranged in general parallelism with one another, interconnected at their tips and spaced at their bottoms.
23. In combination, reenforcing, self-sustained girders, one of which comprises upper and lower horizontal members having diagonal interconnecting braces and the other of which comprises horizontal, spaced members interconnected by vertical braces, said two units being arranged in general parallelism with one another, interconnected at their tips and spaced at their bottoms, and permanent soffits connected to the lower horizontal members.
